DESIGN FOR A LIGHTING FIXTURE BODY

Joshua Gordon Lippincott, Scarsdale, N. Y., assignor to Holophane Company, Inc., New York, N. Y., a corporation of Delaware

Application August 12, 1944, Serial No. 114,849

Term of patent 7 years

(Cl. D48—23)

To all whom it may concern:

Be it known that I, Joshua Gordon Lippincott, a citizen of the United States of America and a resident of Scarsdale, in the county of Westchester and State of New York, have invented a new, original, and ornamental Design for a Lighting Fixture Body, of which the following is a specification, reference being had to the accompanying drawing, forming a part thereof.

In the drawing:

Figure 1 is a perspective view of a lighting fixture body showing my new design; and

Figures 2 and 3 are side and end elevational views of the same.

I claim:

The ornamental design for a lighting fixture body, as shown.

JOSHUA GORDON LIPPINCOTT.
